UNITED STATES PATENT OFFICE

JOSEPF GENICH, OF RACINE, WISCONSIN, ASSIGNOR TO WALKER MANUFACTURING COMPANY, OF RACINE, WISCONSIN, A CORPORATION OF WISCONSIN

LIFTING JACK HANDLE

Application filed July 16, 1932. Serial No. 622,890.

This invention relates to certain new and useful improvements in lifting jack handles, more particularly to a foldable jack handle adapted to be detachably engaged with a lifting jack and to be rotated to operate the jack.

More specifically the jack handle comprises in its preferred form, a pair of pivotally connected rod sections, the free end of one of which is formed to engage with the lifting jack, and the free end of the other section being formed with offset crank and handle members. A slide member or loop on one section is adapted to be engaged with an end portion of the other section to hold the members in substantial alignment when the handle is extended to operative position.

The principal object of this invention is to provide an improved jack handle of the type briefly described hereinabove and disclosed more in detail in the specifications which follow.

Another object is to provide an improved form of pivotal connection for the sections of a foldable lifting jack handle.

Another object is to provide an improved locking means for holding the handle sections in substantial alignment.

Another object is to provide a simple, economical and reliable lifting jack handle of the type herein disclosed.

Other objects and advantages of this invention will be more apparent from the following detailed description of one approved form of lifting jack handle embodying the principles of this invention.

In the accompanying drawing:

Fig. 1 is a plan view of the jack handle in folded position.

Fig. 2 is a similar view of the jack handle in extended operative position, intermediate parts of the two handle sections being broken away.

Fig. 3 is a detail side elevation of the pivotal connection and locking means when the handle is in extended operative position as shown in Fig. 2.

Fig. 4 is a section, taken substantially on the line 4—4 of Fig. 3.

Fig. 5 is a transverse section taken substantially on the line 5—5 of Fig. 4.

Fig. 6 is a transverse section taken substantially on the line 6—6 of Fig. 4.

Fig. 7 is a transverse section taken substantially on the line 7—7 of Fig. 1.

Fig. 8 is a perspective view of the pivoted end portion of one of the handle sections.

Fig. 9 is a perspective view of the locking loop.

The handle comprises a pair of rod sections A and B, each of which is preferably constructed of ordinary bar metal of round cross-section, although it will be apparent as the description proceeds that rod sections of other cross-section than round could be used if desired. The free end portion of section A is provided with suitable means for detachable connection with the rotary driving mechanism of the jack. In the form here shown the free end of section A is stamped into a head of somewhat enlarged square or other non-circular cross-section, as shown at 1, to engage within a socket 2, of similar cross-section, formed in the rotatable driving member 3, of the lifting jack, (see Fig. 2). The member indicated at 3 is usually a hub extending from a driving gear or pinion mounted in the jack. Preferably a pair of locking balls 4 are mounted in a transverse channel 5 formed in the head 1 and are pressed out by an interposed spring 6 against annular lips 7 which hold the balls within the channel 5. These balls may be pressed inwardly against the spring 6 when the head 1 is inserted in the socket 2, and the balls 4 will spring out into the recesses 8 formed in the member 3 to detachably lock the handle in engagement with the lifting jack. This locking means is well known in this art, and is here disclosed by way of example.

The free end portion of the other handle section B is bent at 9 and 10 to form a laterally extending crank portion 11 and a handle 12 at the end of the crank, by means of which the handle is rotated.

The inner end portion of each of the rod sections A and B is stamped down, as indicated at 13, to form a flattened portion 14 and each flattened portion is punched cen-

trally, as indicated at 15, to receive a pivot pin or rivet 16. One face of each flattened portion 14 is preferably formed substantially tangential to one side of the rod section, so that the overlapped end portions of the rod sections will lie substantially in contact with one another. The flattened portion 14 of rod section B is formed closely adjacent the end of the section, but the corresponding flattened portion 14 of rod section A is spaced somewhat from the end of the section so as to leave a short arm 17 projecting beyond the pivotal connection. When the sections are swung into substantial alignment or prolongation of one another, as indicated in Figs. 2, 3 and 4, the short arm 17 of section A will lie parallel to and closely adjacent the rod section B.

A locking member or loop 18 is preferably formed of a small strip or sheet of metal stamped into the form best shown in perspective in Fig. 9. This loop member comprises two similar hollow cylindrical or tubular portions 19 which have open sides merging into one another, each tubular portion being of a size adapted to have a close slidable fit over one of the rod sections A or B. One of the tubular sections 19 of loop member 18 is formed around the rod section B so that it is slidable and rotatable thereon, and when this loop 18 is moved to the position shown in Figs. 2, 3 and 4, the other tubular portion 19 of the loop member will be engaged over the short arm 17 of rod section A, thus holding the two rod members rigidly in substantial prolongation of one another. When the handle is not in use and is to be folded, the loop member 18 is slipped back to some position, such as shown in Fig. 1, after which the members may be swung around the pivot pin or rivet 16 to some suitable folded position, such as shown in Fig. 1. It will be noted that the loop member 18 can be rotated about the rod member B on which it is mounted so as to interfere as little as possible with the folding of the two rod sections into substantially parallel relation with one another.

When the loop member 18 is slipped into locking position, the flattened portions 14 which extend laterally at the sides of the sections A and B at 20 act as stops to limit the movement of the loop to locking position. The inset recesses 13 house and protect the ends of the pivot pin or rivet 16, so that the ends of the rivet cannot be sheared off by the loop 18 or otherwise injured, and the pivotal connection is made more permanent and rigid.

The round-bar material used for the handle sections A and B is particularly adapted to resist the torsional strains to which this rotary handle is subjected and the engaging flat surfaces of the portions 14 at the pivotal joint between these sections relieve the pivot pin 16 of this twisting strain and tend to

maintain a stiff and rigid handle when the sections are extended and locked together by loop 18.

By crimping in the sides of the loop 18 at 21 so that each half of the loop encircles as much as possible of each of the round bar sections A and B, the handle is kept quite stiff and rigid when in extended operative position, and side play or swinging movement between the sections is reduced to a minimum and practically eliminated. The loop 18, which is freely rotatable and slidable on section B, is always held in extended position at one side of the section B so as to slip freely and easily over the end 17 of section A when brought into alignment with this extended portion of the loop.

It will be noted that this jack handle can be formed by a few simple stamping and punching operations. The handle comprises a very few simple and inexpensive parts which may be quickly formed and assembled, and although the parts are comparatively small and light in weight, the handle is strong and rigid when extended for use. The handle is quite compact when folded and the parts all lie flat in substantially a single plane (see Fig. 1), so that comparatively little room is occupied in the tool box.

I claim:

A jack handle comprising a pair of rod sections of substantially circular cross-section, the adjacent ends of said rod sections being stamped to form, in each case, a flattened portion one side of which is substantially tangent to one side of the circular rod, the two sections being overlapped at these stamped ends with the tangential surfaces of the flattened portions in engagement, the flattened portions being formed with aligned openings, a pivot pin secured through the openings, the flattened portion of one section being spaced somewhat from the end of the section so that the rod extends beyond the pivotal connection in the form of a short arm of circular cross-section, and a locking member comprising a loop of sheet material having its opposite sides crimped in to form a pair of connected parallel tubular portions, one of which surrounds and engages one of the rod sections and is slidable and rotatable on this section, and the other of which is adapted to be slidably engaged in a similar manner about the short arm extension of the other section.
